ANTENNA REFLECTOR SYSTEM

Donald Kinnier, Philadelphia, Pa., assignor, by
mesne assignments, to Philco Corporation,
Philadelphia, Pa., a corporation of Pennsylvania

Application August 26, 1944, Serial No. 551,340

14 Claims. (Cl. 250—33.65)

1

My invention relates in general to ultra-high frequency signalling systems, and more particularly to an improved short wave antenna. In general, ultra-high frequency directional radiation antenna systems are arranged to direct their radiated energy against a reflecting surface which determines the field distribution of the radiated energy.

The antenna arrays utilized as the coupling link between the source of energy and the main reflector usually comprise two di-poles properly disposed with respect to the main radiating metallic surface. The correct location of the di-pole antennae has heretofore been a problem since energy radiated from these di-poles and directed toward the main reflecting plate would normally result in interference with the wave guide feeding the di-poles resulting in distortion in the radiation pattern and directional characteristics.

My invention contemplates an ultra-high frequency radiation system which will completely eliminate the interference problem heretofore experienced in signal radiation at comparatively high frequencies.

In accordance with my invention, the ultra-high frequency radiating system comprises essentially a main reflecting surface which may be parabolic or of any other shape dependent upon the directional field characteristic desired. Centrally supported upon the reflecting surface is a rectangular wave guide energized from the source of ultra-high frequency energy. This rectangular wave guide is designed for efficient propagation of the TE_{01} mode of the signal. As is well understood, this oscillation mode results in minimum attenuation in a properly dimensioned rectangular wave guide. At a suitable distance from the main reflecting surface, the rectangular wave guide terminates in a transverse cylindrical cavity of one wave guide wave length for the operating frequency.

The cylindrical cavity is appropriately matched with the rectangular wave guide and is proportioned for efficient propagation of the TM_{01} oscillation mode. The ends of the cylindrical cavity are sealed in a manner to be described. Coupled into the sealed ends of the cylindrical guide are di-pole radiators each approximately $\frac{1}{2}$ wave length long. These di-pole radiators are axially mounted upon the cylindrical wave guide such that approximately $\frac{1}{4}$ wave length section extends into the cylindrical guide and approximately $\frac{1}{4}$ wave length is exposed. Slight adjustments of the lengths are made to secure

2

impedance matching between the di-pole and cylindrical wave guide. Accordingly, energy is coupled from the sources of oscillation through the rectangular wave guide and cylindrical cavity to the individual di-pole radiating units.

The lengths of the di-pole antennae extending into the cylindrical cavity are positioned at a point of maximum field intensity and accordingly the energy radiated from the exposed portion of the di-pole is comparatively large, and high radiation efficiency is obtained. This energy is directed by suitable means against the main reflecting surface supporting the wave guide and di-poles and is re-radiated into space from this main surface.

The di-pole supporting means precludes interference between these antennae and the main reflecting elements since the di-poles are spaced from the supporting means by a sufficient distance to prevent the supporting structure from interfering with the radiation from the di-poles to the reflector. The radiating unit is particularly flexible since the di-poles are so located that various reflectors may be used to obtain control of the field distribution. Thus the reflectors may also be located about the di-pole at suitable positions such that the main guide may be brought through the frequency reflector at other than a centrally located position.

It is thus an object of my invention to provide an improved ultra-high frequency radiating structure.

Another object of my invention is to provide a radiating system including di-poles and a main reflector situated so that a minimum of interference is obtained therebetween.

A further object of my invention is to provide a radiation system utilizing di-poles energized from a cylindrical wave guide.

These and other objects of my invention will now become apparent from the following detailed specification taken in connection with the accompanying drawings in which

Figure 1 is a front view of the radiating structure.

Fig. 1a is a perspective view of the showing of Fig. 1.

Figure 2 is a side view of the structure illustrated in Figure 1.

Figure 3 is a front view of an end plate for a cylindrical cavity.

Figure 4 is a cross-sectional view of the end plates taken along the line 4—4 of Figure 3.

Figure 5 is a front view of a modified end plate for a cavity; and

Figure 6 is a cross-sectional view taken along the line 6—6 of the end plate illustrated in Figure 5.

Referring now to Figures 1 and 2, there is shown a large metallic reflecting surface 11, parabolically or otherwise shaped to provide a desired field distribution. Extending through a centrally located opening 12 in the main reflector 11 is a rectangular wave guide 13. The wave guide 13 is joined at its lower end 14 to the source of energy to be radiated.

Since the TE_{01} mode of propagation is transmitted through wave guides with minimum attenuation, the rectangular wave guide 13 is proportioned for the propagation of this oscillation mode.

The upper end of the rectangular wave guide 13 is suitably cut to support the circular wave guide 15. A large opening is cut into the lower surface of circular wave guide 15 to provide a continuous passage from the inside of wave guide 13 to the inside of wave guide 15. The transition between the rectangular wave guide 13 and the circular guide 15 is such that proper matching is obtained between the two so that a maximum energy transfer is effected.

The cylindrical section 15 is so proportioned that propagation therein will occur at the TM_{01} mode. The field distribution for this mode of oscillation within the cylindrical section 15 is such that maximum electric field intensity is obtained along the axis of the cylinder. The length of the cylindrical section 15 is one wave length so that proper resonance may be established therein.

Suitably supported upon the ends of the cylindrical wave guide 15 are di-pole antennae 21 and 22. Each of these individual di-poles is approximately $\frac{1}{2}$ wave length long, and extends as at 23 into the cylindrical section 15 for approximately $\frac{3}{4}$ wave length. Accordingly, approximately $\frac{1}{4}$ wave length of each of the di-poles 21 and 22 is exposed. The supporting means for the di-pole antennae 21 and 22 provide suitable insulation between the di-poles and the walls of the cylindrical guide 15. These supports will be described in greater detail later. Accordingly it may be seen that energy from the oscillating source impressed upon the wave guide 13 is carried thereby through the opening 12 in the reflecting surface 11 and into the cylindrical section 15 wherein a resonant condition is established. The di-poles 21 and 22 absorb energy from the oscillating system within the wave guide 15 and this energy is radiated from the exposed ends thereof.

As illustrated in Figures 1 and 2, and as will be described in greater detail later, parasitic reflectors 31 and 32 are provided for the di-poles 21 and 22 respectively.

These reflectors 31 and 32 are mounted directly above their associated di-poles, and are joined electrically to the walls of the wave guides 15. As is well understood, these parasitic reflectors when combined with their associated di-poles result in directional radiation towards the main reflecting surface 11. Accordingly the greater part of the energy flowing from di-poles 21 and 22 is directed to the reflecting surface 11 whereat it is re-radiated into space in a directional manner as determined by the nature of the reflecting surface 11.

As illustrated, the structure provides for minimum interference between the di-pole radiators and the reflecting surface 11, since the structure is so arranged that di-poles 21 and 22 are spaced

substantially from the surface of the support and wave guide 13.

Obviously the nature of the reflectors for directing the radiating energy towards the main reflecting plate 11 may be varied as required by the field distribution desired. For example, the reflectors 31 and 32 which are connected to the cylindrical guide 15 may be replaced by corner reflectors which will also serve to direct the greater part of the radiated energy against the reflecting plate 11.

The di-pole supporting means are illustrated in Figures 3 to 6 inclusive. In one modification of a di-pole support as illustrated in Figures 3 and 15 4, a circular metallic plate 41 serves as the end plate for the cylindrical cavity 15. Thus, the metal plate 41 is equal in diameter to the wave guide 15 and has an opening 42 to support an insulating insert 43 which may be secured in any 20 convenient manner. Centrally located in the insulating insert 43 is the di-pole 21 which as illustrated in Figure 4 extends through a perforation 44 within the insulating insert so that approximately $\frac{1}{4}$ wave length of the di-pole will be positioned within the cavity 15 and the other approximately $\frac{1}{4}$ wave length of the di-pole 21 will serve as the radiating element.

The parasitic reflector 31 approximately $\frac{1}{4}$ wave length long is supported within a perforation 45 in the metallic end plate 41. The distance between the di-pole radiator 21 and the parasitic reflector 31 is selected to give the desired radiation toward the primary reflector. It may thus be seen from Figures 3 and 4 that the insulating 35 insert 43 is approximately $\frac{1}{2}$ wave length in diameter. The end plate structure of Figures 3 and 4 is of course used at each of the ends of the cylindrical wave guide 15. Although the wave guide 13 is shown centrally located in the reflector 11, it 40 will now be obvious that it may be brought in from other angles as from the side, since the secondary reflector 31 may be rotated about the main di-pole 21 to provide desired directing toward the primary reflector 11.

Another type of di-pole support is illustrated in Figures 5 and 6. Here again, as in the type illustrated in Figures 3 and 4, a metallic end plate 51 of the diameter of the cylindrical guide 15 is utilized as the basic supporting member. An essentially circular perforation 52 of approximately $\frac{1}{2}$ wave length diameter is concentrically located within the end plates 51. Extending into the circular opening 52 is an integral extension 53 of the metallic plate 51. The extension 53 is $\frac{1}{4}$ wave length long and accordingly reaches the center of the end plate 51. As illustrated, a di-pole radiator, such as 21, approximately $\frac{1}{2}$ wave length long is securely supported upon the inner 60 end of the metallic extension 53 such that approximately $\frac{1}{4}$ wave length of the di-pole extends normal to each surface of the metallic end plate 51.

As is well understood in the art, a $\frac{1}{4}$ wave length of transmission lines short circuited at one end presents comparatively high impedance at its input terminals. In this manner the $\frac{1}{4}$ wave length metallic supporter 53 serves as an insulator between the metallic end plate 51 and the attached di-pole 21. In order to obtain the proper 65 directional characteristics, a parasitic reflector 56 approximately $\frac{1}{4}$ wave length is secured within a perforation 57 in the metallic end plate 51. The reflector 56 is positioned directly above the exposed length of the di-pole radiator 21 so that

energy reflected from the latter di-pole is directed against the metallic reflector 11.

In the application of an end plate as illustrated in Figures 5 and 6, the plates are securely fastened to the ends of the cylindrical cavity 15 in the manner illustrated in Figures 1 and 2. Accordingly it may be seen that the radiating structure illustrated in Figures 1 and 2 provides a convenient flexible means for directional signal transmissions. The radiating di-poles are conveniently coupled to the energy source in a manner which provides a maximum overall efficiency and energy transfer.

The field distribution of the radiating signal may be varied simply by a variation in the reflecting surface or in the type of reflector used behind the radiating di-poles.

It is thus evident that this flexible radiating structure may be subject to various modifications without departing from the scope of the invention. Accordingly I prefer not to be bound by the specific disclosures hereinabove set forth but by the appended claims.

I claim:

1. An ultra-high frequency antenna system comprising a reflector; di-poles each approximately one-half wave length long for radiating energy to said reflector and a feeding system for propagating energy to said di-poles including a completely enclosed cavity resonator, said di-poles being insulatedly mounted in said cavity resonator.

2. An ultra-high frequency antenna system comprising a reflector; di-poles for radiating energy to said reflector and a feeding system for propagating energy to said di-poles including a completely enclosed and sealed cavity resonator, said di-poles being insulatedly mounted in said cavity resonator at the point of maximum field intensity.

3. An ultra-high frequency antenna system comprising a reflector; di-poles for radiating energy to said reflector and a feeding system for propagating energy to said di-poles including a cavity resonator, said di-poles being insulatedly mounted in said cavity resonator and protruding therefrom.

4. An ultra-high frequency antenna system comprising a reflector; di-poles for radiating energy to said reflector and a feeding system for propagating energy to said di-poles including a cavity resonator, said di-poles being insulatedly mounted in said cavity resonator and protruding therefrom a quarter of a wave length.

5. An ultra-high frequency antenna system comprising a reflector; di-poles for radiating energy to said reflector and a feeding system for propagating energy to said di-poles including a cavity resonator, said di-poles being insulatedly mounted in said cavity resonator extending within said cavity resonator for one quarter of a wave length and protruding from said cavity resonator for one quarter of a wave length.

6. An ultra-high frequency antenna system comprising a reflector; di-poles for radiating energy to said reflector and a feeding system for propagating energy to said di-poles including a cavity resonator, and a wave guide of rectangular cross-section energized by high frequency energy coupled to said cavity resonator, said di-poles being insulatedly mounted in said cavity resonator.

7. An ultra-high frequency antenna system comprising a reflector; di-poles for radiating energy to said reflector and a feeding system for

propagating energy to said di-poles including a cavity resonator, and a wave guide of rectangular cross-section energized by high frequency energy coupled to said cavity resonator, said di-poles being insulatedly mounted in said cavity resonator at opposite ends thereof.

8. An ultra-high frequency antenna system comprising a reflector; di-poles for radiating energy to said reflector and a feeding system for propagating energy to said di-poles including a one wave guide wave length cavity resonator and a wave guide of rectangular cross-section energized by high frequency energy coupled to said cavity resonator, said di-poles being insulatedly mounted in said cavity resonator.

9. An ultra-high frequency antenna system comprising a reflector; di-poles for radiating energy to said reflector and a feeding system for propagating energy to said di-poles including a one wave guide wave length cavity resonator and a wave guide of rectangular cross-section energized by high frequency energy coupled to said cavity resonator, said di-poles being insulatedly mounted in said cavity resonator at opposite ends thereof.

10. An ultra-high frequency antenna system comprising a reflector; di-poles for radiating energy to said reflector and a feeding system for propagating energy to said di-poles including a cavity resonator, said di-poles being insulatedly mounted in said cavity resonator and parasitic reflectors extending from said cavity resonator.

11. An ultra-high frequency antenna system comprising a reflector; di-poles for radiating energy to said reflector and a feeding system for propagating energy to said di-poles including a cavity resonator, and a wave guide of rectangular cross-section energized by high frequency energy coupled to said cavity resonator, said di-poles being insulatedly mounted in said cavity resonator, said rectangular cross-sectional wave guide extending through an opening in said reflector and said cavity resonator having its axis at right angles to the longitudinal axis of said wave guide at the point of coupling.

12. An ultra-high frequency antenna system comprising a reflector; di-poles for radiating energy to said reflector and a feeding system for propagating energy to said di-poles including a wave guide and a cavity resonator proportioned to propagate the TM_{01} mode, said wave guide and cavity forming a continuous passage, said di-poles being insulatedly mounted in said cavity resonator.

13. An ultra-high frequency antenna system comprising a reflector; di-poles for radiating energy to said reflector and a feeding system for propagating energy to said di-poles including a cavity resonator proportioned to propagate the TM_{01} mode and a wave guide of rectangular cross-section proportioned for the propagation the TE_{01} mode, said di-poles being insulatedly mounted in said cavity resonator.

14. An ultra-high frequency antenna system comprising a reflector; di-poles for radiating energy to said reflector and a feeding system for propagating energy to said di-poles including a cavity resonator, and a wave guide of rectangular cross-section energized by high frequency energy coupled to said cavity resonator, said di-poles being insulatedly mounted in said cavity resonator, said rectangular cross-sectional wave guide extending through an opening centrally located in said reflector and said cavity resonator having its

axis at right angles to the longitudinal axis of said wave guide at the point of coupling.
